MAGNETIC DISK, FIXED HEAD FILE

Edward D. Lucey, Los Gatos, and Dallas G. Molerin, San
Jose, Calif., assignors to International Business
Machines Corporation, Armonk, N.Y.

Filed Jan. 30, 1970, Ser. No. 21,172

Term of patent 14 years

Int. Cl. D14—02

U.S. Cl. D26—5

FIG. 1

FIG.2

FIG. 1 is a front perspective view of a magnetic disk, fixed head file showing our design;

FIG. 2 is an enlarged view showing the upper left portion of the file of FIG. 1 in greater detail;

The design is characterized by the upper left portion of the article which is more clearly illustrated in FIG. 2.

The sides and back of the article not shown are plain and conventional.

We claim:

The ornamental design for a magnetic disk, fixed head file, as shown and described.
